UNITED STATES PATENT OFFICE.

FREDERICK MAYOR, OF NEW YORK, N. Y.

SPOOL-HOLDER

No. 918,180.

Specification of Letters Patent.

Patented April 13, 1909

Application filed June 27, 1908. Serial No. 440,632

To all whom it may concern:

Be it known that I, FREDERICK MAYOR, a subject of the Emperor of Austria-Hungary and King of Hungary, and a resident of the 5 city of New York, borough of the Bronx, in the county and State of New York, have invented a new and Improved Spool-Holder, of which the following is a full, clear, and exact description.

10 This invention is an improvement in
spool holders, belonging to that class of such
devices adapted to carry a number of spools
of thread and be applied to a sewing ma-
chine, the spools being locked in the holder
15 to prevent their theft or unauthorized re-
moval.

It is the purpose of the invention to provide a holder of this nature adapted to be applied to the machine either vertically or horizontally, the same embodying two heads arranged at the opposite ends of a cushioned stem, one of said heads being permanently attached to the stem and provided with a number of spool-supporting pins, and the other head detachably applied to the stem and secured thereto by a novel lock.

Reference is to be had to the accompanying drawings forming a part of this specification, in which similar characters of reference 30 indicate corresponding parts in all the views.

Figure 1 is a central longitudinal section through the preferred form of my improved spool holder; Fig. 2 is a section through the locking head of the holder substantially on the line 2—2 of Fig. 1, looking in the direction of the arrow; Fig. 3 is a fragmentary sectional view similar to the section shown in Fig. 2 but with the locking bolt in a position to permit of the removal of the head from the stem; Fig. 4 is a section on the line 4—4 of Fig. 2, looking in the direction of the arrow; and Fig. 5 is a perspective view of the lock barrel and the key for operating the same.

45 More specifically described, the construction of the holder includes a hollow stem 10, to the opposite ends of which are applied heads 11 and 12 respectively, the head 11 being threaded on the stem or otherwise
50 permanently attached thereto, and the head 12 detachably secured to the stem by a locking mechanism hereinafter described. Each head is provided with a boss on its inner face to form a substantial bearing with the stem,
55 and between these bosses is placed a collar or sleeve 12^a of rubber or other equivalent

elastic material to provide a cushion between the two heads, which serves to absorb the vibration when the holder is in use on the machine.

On the inner face of the head 11 a number of bosses, similar to the one at the center, are circularly arranged and receive the threaded ends of an equal number of spool-supporting pins 13, the pins being of such length as to project close to the inner face of the head 12, as clearly shown in Fig. 1. The head 12 is constructed on its outer face with a diametrically arranged bead or rib 14 which serves as a housing for the lock above mentioned, the same consisting of a bolt 15 70 slidable in a bore longitudinally of the rib, and a barrel 16 for actuating the bolt and revolvably mounted at right-angles thereto. The bolt passage at one side intersects the 75 bores for receiving the barrel 16 and the stem 10, and at these points the diameters of the barrel and the stem are reduced as respectively indicated at 17 and 18, which permits of the free passage of the bolt, which, in its 80 normal position, under the influence of a spring 19, as shown in Fig. 2, locks the barrel and pin to the head. The spring 19 which is interposed between the inner end of the bolt and the bottom of its bore or passage, 85 tends to force the bolt in contact with a plug 20 threaded into the outer end of the passage after the spring and bolt are inserted. At that point of the length of the bolt which is arranged between the stem and barrel when 90 the bolt is in locking position, is provided a circumferential groove 21, similar to those provided in connection with the stem and barrel, and the bolt is further provided with adjacent circumferential grooves 22, the 95 inner one of which connects with the bore of the barrel when the bolt is in locking position, as shown in Fig. 2. The barrel 16 is held against withdrawal not only by the bolt but also by a pin 23, projecting into a 100 circumferential groove 24. The barrel is also longitudinally slotted as indicated at 25 for the insertion of a key such as shown in Fig. 5. This key in connection with a leaf 26 arranged in the grooved portion of the barrel 105 operates when the key is inserted and revolved to successively engage with the grooves 22 and force the bolt against the tension of the spring 19 until the groove 21 registers with the pin, in which position the 110 head may be removed and applied to the stem 10. I have shown the key provided

with notches at opposite sides to register with the circumferential groove 24 in the barrel, and a similar notch at its end to register with a pin 27 projecting from the 5 head to the inner end of the barrel, this particular construction, however, being susceptible of many modifications according to the character of the key which is to be used. The exposed hollow end of the stem 10 10 admits of the holder being vertically supported on the spool 10 of the sewing machine, or if desired the holder may be supported on this pin in a horizontal position, for which purpose I provide a similar bore 28 in one end of 15 the rib 14.

Having thus described my invention, I claim as new and desire to secure by Letters Patent:

1. The combination of a stem having 20 heads secured to the opposite ends thereof, one of which is provided with spool-supporting pins, and a cushion interposed between the two heads and arranged on the stem.
2. The combination of a stem having a circumferential groove near one end thereof, a 25 head secured to the other end thereof, a head having a bolt for engaging the groove of the stem and locking the head thereto, a barrel revolvable in the last mentioned head 30 having key-controlled means for actuating the bolt, and spool-supporting pins attached to one of said heads and projecting close to the other head.
3. The combination of a stem having a

head attached to one end, a second head 35 having a bolt for locking it to the other end of the stem, a key-operated barrel carried by the second head for actuating the bolt, and spool-supporting pins arranged between the heads.

4. The combination of a stem having a head permanently attached to one end provided with spool-supporting pins and a circumferential groove at its opposite end, a second head having a spring-pressed bolt 45 adapted to engage the groove of the stem when the head is applied thereto, and provided with a circumferential groove, and a key-operated barrel revolvable in the second head, having means for forcing the bolt 50 against the tension of the spring to bring the said groove in register with the stem.

5. A spool holder having a hollow stem adapting it to receive the spool-supporting pin of a sewing machine, a head attached to 55 one end of the stem, having spool-supporting pins, and a head locked to the opposite end of the stem, having a bore for receiving said spool-supporting pin of the machine and supporting the holder in an approximately horizontal position.

In testimony whereof I have signed my name to this specification in the presence of two subscribing witnesses.

FREDERICK MAYOR.
